UNITED STATES PATENT OFFICE.

ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

CONTROL AND RELEASE DEVICE.

1,330,411.

Specification of Letters Patent. Patented Feb. 10, 1920.

Application filed March 22, 1916. Serial No. 85,941.

To all whom it may concern:

Be it known that I, ERNEST B. THURSTON, a citizen of the United States of America, residing at Toledo, Lucas county, Ohio, have 5 invented new and useful Control and Release Devices, of which the following is a specification.

This invention has utility when incorporated in control and release devices, especially as an automatic lock-out of power current for elevators when an elevator door is open.

Referring to the drawings:

Figure 1 is a fragmentary view of an elevator well looking out toward the door, with the car approaching the floor, showing an embodiment of the invention in the elevator well;

Fig. 2 is a view of an embodiment of the invention in the door lock of Fig. 1, with the door closed;

Fig. 3 is a view of the mechanism of Fig. 2 as coacting in releasing position;

Fig. 4 is a side elevation of the first series 25 of levers;

Fig. 5 is a view on an enlarged scale of the rockable dog and its mounting; and

Fig. 6 shows an anti-friction connection between the first and second series of levers.

In the elevator well 1 at the landing 2 is disposed the slideable door 3. As the car 4 approaches the landing 2, the interceptor 5 comes into position at the nose of the dog 6. This device has special adaptation in connection with elevators of the so-called automatic or push button type, and embodies a safety device precluding opening of a door at any floor while the car is away from or traveling past such floor, for should the 35 actuating member 7 be grasped to throw the dog 6, the movement of the member 5 striking a side of the nose of the dog 6 would rub therealong and tend to rock this dog 6. There would be no holding of the 40 dog 6 by the member 5 as an abutment. The actuating member 7 is a lever having its fulcrum bearing 8 and the short arm 9 coacting in the rocking of the lever to compress the yieldable means or spring 10 and there- 45 by tending to throw the release member or latch 11 having the fulcrum bearing 12. These pivot or fulcrum bearings 8 and 12 may, in the embodiment of this device for

elevator purposes, be mounted on or in a sliding door movable toward a fixed lock 55 casing or box 13 carried by the well.

The actuating member has a lever arm 14 extending through a recess 15 of the casing 13 to engage the arm 16 of the bell crank lever having the fixed fulcrum 17 in the 60 casing 13. This bell crank lever has its second arm 18 upwardly extending and loosely carrying the pin 19 which has fast therewith outside of the casing 13 the arm 20 carrying the pivot pin 21 for mounting 65 the rockable dog 6. This dog 6 has its position normally maintained by the counter-weight 22, while the stability of this dog is further maintained by the coil spring 23 coacting with the lug 24 carried by the pin 70 21 and the lug 25 carried by the dog. The dog is accordingly free to be rocked either up or down by the moving interceptor 5 but is normally maintained in a position to be confronted by or abut directly the interceptor 5 when the interceptor 5 is stationary and the elevator car is at a landing.

In this abutting action, any rocking of the bell crank levers 16, 18 tending to throw the pin 19 would leave the pin 21 fixed and the 80 rocking of lever 18 would throw the arm 26 fast on the shaft 19 upward against the resistance of the spring 27 from the position of this arm 26 as adjusted by the stop 28 co-acting with the arm 18. The arm 26 would 85 not be lifted were the dog 6 not intercepted by the member 5. This lifting of the arm 26 of the second bell crank 20, 26, coacts with the shoe or bearing 29 of the arm 30 of the third bell crank lever having its ful- 90 crum 31 in the casing 13. In any rocking of this arm 30 of the bell crank lever 30, 32, the arm 32 is rocked away from its holding position above the latch head end of the lever 11 protruding through the opening 33 and 95 thus engaged in the casing 13. This rocking of the arm 32 is against the action of the spring 34 from the arm 35 of the spring poised lever having the fulcrum 36 in the casing 13. This spring poised lever has its 100 second arm 37 coacting with the spring 38 forcing this arm 37 toward the latch recess 33 in the casing 13. This coaction of the second series of levers 30, 32; 35, 37, is such that with the latch 11 in the recess 33, the lever 105 35, 37, has its spring 34 acting to hold the

arm 32 over the latch head of the lever 11 precluding any release of such latch head except through the interaction of the first series of levers 16, 18; 20, 26, upon the second series of levers 30, 32; 35, 37.

With the latch head of the lever 11 out of the casing 13, the action of the spring 38 has thrown the arm 37 of the lever 35, 37, against this latch opening 33 to obstruct said opening 33 as to entrance of the latch 11 thereinto. This causes the spring 34 to rock the lever member 30, 32, so that the contacts 39, 40, 41, 42, are open and arm 32 is away from the latch recess 33. The rocking of the lever 30, 32, whether from the arm 26 or from lever 32, 35, moves the switch contacts 39, 40, carried by the arm 30 away from the fixed contacts 41, 42, and thus breaks the circuit 43, which may interact to preclude driving of the car when this switch is open. As this switch is open only when the door is open and is so opened by the opening of the door, by leaving the door open there is an automatic safety device precluding shifting 25 of the elevator car away from a landing with the door open. Further, the door may not be open unless the car is at a landing in the normal manipulation of the apparatus. Even with any attempt at tampering with 30 the apparatus, as by insertion of a member in the latch opening 33, the switch 39, 40, 41, 42, is only closed while such member is maintained in position.

These connections are simple in their interaction, for the dual movements are protected against tampering, may be assembled as a safety device unit before installation, and are most easily and readily operable with the usual freedom of a door release device. However, supplemental freedom in ease of operation may be attained by providing the second bell crank with the arm 44 instead of the arm 26 and mounting on said arm 44 the anti-friction roller 45 for anti-friction coaction in the latch freeing travel with the arc shoe 46 of the arm 30 of the third bell crank lever.

The switch 39, 40; 41, 42 is so disposed with the electric connections that a child inserting its finger in the latch opening 33 may not receive an electric shock.

What is claimed and it is desired to secure by United States Letters Patent is:

1. A control apparatus comprising a lock housing, a relatively traveling pivoted latch, said housing having an opening providing a latch seat, an actuator carried with the latch, movable independently of the latch and having a portion extending into the housing, a first device in the lock housing operable by the actuator independently of affecting the latch, a second device, a release member for the latch, a setting member for the release member, and means for causing the first device to coact with the second de-

vice for shifting the release member into latch freeing position against the resistance of the setting member.

2. A control apparatus comprising a lock housing, a relatively traveling pivoted latch, 70 said housing having a latch seat, an actuator carried with the latch, movable independently of the latch and having a portion extending into the housing, a first device in the lock housing operable by the actuator independently of affecting the latch, a second device, a release member for the latch, a setting member for the release member, means for causing the first device to coact with the second device for shifting the release member into latch freeing position 75 against the resistance of the setting member until the latch is withdrawn, and a spring for holding the setting member in position 80 to be moved by the latch entering its housing seat.

3. A control apparatus comprising a lock housing, a relatively traveling pivoted latch, said housing having a latch seat, an actuator carried with the latch, movable independently of the latch and having a portion extending into the housing, a first device in the lock housing operable by the actuator, independently of affecting the latch, a second device, a release member for the latch, 90 a setting member for the release member, means for causing the first device to coact with the second device for shifting the release member against the resistance of the setting member into latch freeing position, 95 and connecting means between the setting member and the release member holding the release member away from locking position when the setting member is in position to obstruct entrance of the latch to the latch 100 seat.

4. A control apparatus comprising a lock housing, having a latch seat, a latch movable into said seat, an actuator carried with the latch and extending into the housing, a first device in the housing operable by the actuator, a second device, a release member for the latch, a setting member for the release member, means for causing the first device to coact with the second device for 110 shifting the release member against the resistance of the setting member into latch freeing position, and spring and pin connecting means between the setting member and the release member throwing the releasing member in latch locked position when the latch throws the setting member away from obstructing latch entrance to the latch seat.

5. A control apparatus comprising a lock 125 housing having a latch seat, a latch movable into said seat, an actuator carried with the latch and extending to enter the housing, a first device in the housing operable by the actuator, a second device, a release member 130

for the latch, a setting member for the release member normally actuatable into position to obstruct latch entrance to the latch seat, means for causing the first device to 5 coact with the second device for shifting the release member, and connecting means between the members causing the setting member in latch seat obstructing position to hold the release member away from locking position.

6. Control apparatus including a pivoted latch, a holding seat for the latch, a setting member obstructing the seat when the latch is clear of the seat, and a release member 15 operable from the setting member for locking the latch in the seat.

7. Control apparatus including a latch, a holding seat for the latch, a release member for locking the latch in the seat, and 20 a setting member obstructing the seat when the latch is clear of the seat abutted by the latch in the seat to throw the release member into latch locking position.

8. Control apparatus including a movable latch, a holding seat for the latch, and relatively movable release and setting members, the latter member obstructing the latch seat when the latch is out and the former member obstructing the latch seat when the 25 latch is in to preclude latch removal therefrom.

9. Control apparatus including a movable latch, a holding seat for the latch, a release member movable to lock the latch in its seat, a setting member for the release member, and a spring normally urging the setting member to obstruct entrance of the latch to its seat and coacting in such position to shift the release member away from seat obstructing position. 35

10. Control apparatus including a movable latch, a holding seat for the latch, a release member movable to lock the latch in its seat, a setting member for the release member, and connecting means including 40 45 a spring between the members causing the setting member in latch seat obstructing position to hold the release member away from locking position.

11. Control apparatus including a movable latch, a holding seat for the latch, relatively movable release and setting members, the latter member obstructing the latch seat when the latch is out and the former member obstructing the latch seat when the latch 50 is in to preclude latch removal therefrom, a switch opened by the release member, and means coacting with the setting member to retain the switch opened.

In witness whereof I affix my signature. 55 60

ERNEST B. THURSTON.
